[57] **CLAIM**

The ornamental design for a trunk lid, as shown and described.

DESCRIPTION

FIG. 1 is a front elevational view of a trunk lid showing our new design;

FIG. 2 is a right side elevational view, the left side being a mirror image thereof;

FIG. 3 is a top plan view thereof;

FIG. 4 is a rear elevational view thereof;

FIG. 5 is a bottom plan view thereof.

The broken line showing of a trunk bottom in FIGS. 1, 2 and 4 is for illustrative purposes only and forms no part of the claimed design.

FIG. 1

FIG. 2

FIG.3

FIG.4

FIG. 5
